UNITED STATES PATENT OFFICE.

EDWIN B. STIMPSON, OF BROOKLYN, NEW YORK, ASSIGNOR TO EDWIN B. STIMPSON COMPANY, OF BROOKLYN, NEW YORK.

CUSHION-TUFTING AND RIVET-SETTING MACHINE.

Application filed March 5, 1925. Serial No. 13,044.

This invention relates to a machine for use in tufting cushions by setting tufting members of the rivet type therein, and also to a method for performing a tufting operation.

5 The invention includes a vertically movable anvil member arranged to be lifted into engagement with the underside of a cushion and to be locked in its raised position to provide an anvil surface with which rivet setting mechanism is arranged to cooperate in setting a tufting member in place in the cushion.

Another feature of the invention resides in the provision of means automatically operable following the operation of the rivet setting mechanism for unlocking the anvil member to permit the anvil member to descend to a lowered position to provide for changing the position of the work.

20 The anvil elevating means and the rivet setting mechanism are preferably arranged to be operated through the manipulation of a pair of foot treadles mounted adjacent each other for separate and successive operation to raise the anvil member to operative position and then to actuate the rivet setting mechanism.

The locking means for the anvil member preferably consists of a spring-pressed bolt 30 which automatically engages with a stationary part when the anvil member has reached its elevated position. Means operating automatically upon the retraction of the rivet setting mechanism retracts the bolt from its locking position and releases the anvil member to descend to its lowered position.

Another feature of the invention resides in the use of shock-absorbing means for 40 cushioning the descent of the anvil member and preventing the production of noise.

Other features of the invention will be hereinafter referred to.

In the drawings, in which a preferred embodiment of the invention has been selected for illustration.

Figure 1 is a view in side elevation of a cushion tufting machine embodying the invention.

50 Figure 2 is a view partly in front elevation and partly in vertical section showing a portion of the machine shown in Figure 1, on an enlarged scale.

Figure 3 is a view in transverse horizontal section taken on the line 3—3 of Figure 2.

Figure 4 is a vertical section on an enlarged scale showing a detail of the mechanism shown in Figure 2 with the parts lowered or in inoperative position.

Figure 5 is a view similar to Figure 4 showing the parts locked in raised or operative position.

Figure 6 is a view similar to Figure 5 showing the condition of the parts when unlocking mechanism is being operated.

Figure 7 is a view in plan of a spring device used in the invention.

Figure 8 is a view in side elevation of an anvil member forming part of the invention.

Figure 9 is a view similar to Figure 8 taken at right angles to the view shown in Figure 8.

Figure 10 is a sectional view on an enlarged scale showing in detail the condition of the work following an operation of the machine.

Figure 11 is a view in side elevation and vertical section of a shock-absorbing device forming part of the invention.

Referring to the drawings for a more detailed description of the invention, in Figure 1 there is shown a tufting machine embodying the invention and including a base member 10 from which a vertical standard or frame member 11 projects upwardly to support a head member 12 on which rivet feeding mechanism 13 and rivet setting mechanism 14 are carried.

Projecting forwardly from the upper extremity of the standard 11 is a table or shelf member 15 on which the work may be received as a preliminary to the carrying-out of a tufting operation thereon. The shelf 15 is supported on bracket members 16 which are bolted directly to the standard 11 and the base portion of the head member 12, the outer extremities of the bracket member 16 being in turn supported by angularly disposed bracket members 17 attached at their lower ends to a vertical standard and guide member 18.

The guide member 18 takes the form of an extension of a vertically projecting frame member 20 mounted on a forward portion of the base member 10 already referred to. The guide member 18 is provided with a slideway 21 in which a vertically movable anvil member 22 is mounted for sliding movement. The anvil member 22 is provided at its upper extremity with an upset-

ting and forming head member 23 against which the tufting rivet is forced for an upsetting operation thereon.

The vertically movable anvil member 22 is operated through an arm 23' which passes through a slot formed for the purpose in the rear wall of the guide member 18 and pivotally engages at 24 with the anvil member 22 passing into a slot 25 formed in the anvil member 22 for the purpose. The other end of the arm 23' is pivoted at 26 to a lever 27 equipped with a foot treadle 28 at its outer extremity and pivoted at a mid point 29 to the forward standard or frame piece 20. Through the arrangement described, depression of the foot treadle 28 acts to elevate the anvil member 22 from a lowered to the elevated position shown in Figures 1 and 2 of the drawing.

In order to lock the anvil member in its raised position, a spring-pressed bolt 30 is slidably mounted for lateral movement in a slideway 31 formed in the anvil member for the purpose. A recess 32 extending longitudinally in the side of the anvil member adjacent the slideway 31 forms a seat for a spring 33 which engages the adjacent end of the bolt 30 and causes the bolt to move into an opening 34 in the frame member 18 to thereby lock the anvil member in fixed position within the slideway 21.

In order to unlatch or unlock the anvil member 22 when it is necessary to cause the anvil to descend to provide for changing of the position of the cushion 35 or other work, a latch operating bar 36 is mounted to slide in a vertically extending groove 37 formed in the anvil member 22 and to engage a bolt operating member 38 mounted for partial rotation on a pin 39 extending into the bolt 30 and having sliding movement in a notch 40 in the wall of the anvil member 22. The spring 33 has a section 33' arranged to engage the member 38 and normally hold the same in the position shown in Figure 5 of the drawing. The bolt operating member 38 is mounted to slide and rock within a notch or recess 41 formed in the forward face of the anvil member 22. The bolt operating member is provided with a tooth 42 for engagement by a cam member 43 formed in the vertically movable rod 36.

With the construction described, the operation of the latch operating mechanism takes place as follows: Upon a descending movement of the rod 36 which accompanies the operating movement of the rivet setting device 14, the cam member 43 on the slide bar 36 engages the tooth 42 on the latch operating member 38 and partially rotates the member 38 in its seat thereby permitting the cam member 43 to pass downwardly past the position of the member 38 without operating the same other than to produce the yielding rotative movement referred to.

Upon the return or upward movement of the slide bar 36 which accompanies the return or idle stroke of the rivet setting device 14, the upper or cam face of the cam member 43 engages the lower surface of the tooth 42 and forces the member 38 to the right as is shown in Figure 6 of the drawing. It will be seen that the translational movement of the member 38 which is thus produced brings about the retraction of the bolt 30 from its locking engagement with the recess 34. The result is that the anvil member 22 is released from its locked position and is free to descend in the guideway 21.

In order to cushion the descending movement of the anvil member 22, a shock-absorbing device 43' is connected at one end to the arm 23' and at the other end to a fixed point on the base member 10. With this arrangement a dash-pot effect is produced which cushions the descending movement of the arm 23' and eliminates impact or clash of the descending parts with accompanying noise.

The descending movement of the arm 23' is facilitated through the use of a coiled spring 44 attached at one end to the pivot pin 26 and at the other to an arm 45 used in the operation of the rivet setting mechanism.

The arm 45 is pivoted at 46 on the standard 11 and is provided at its forward end with a foot treadle 47. The other end of the arm or lever 45 is pivotally connected at 48 with a link 49 connected to a rock arm 50 pivotally mounted at 51 on the head member 12 of the machine. The rock arm 50 has a link connection 52 with the joint 53 of a pair of toggle arms 54 which operate the rivet setting device 14. Another link 55 extends from the rock arm 50 and operates ratchet mechanism 56 forming part of the rivet feeding mechanism 13. In order to raise the treadle member 47 to its elevated position following an operation thereof, a spring 57 connected at one end to the arm 45 is attached at its other end to a hook 58 on the forward face of the standard frame member 11. An adjustable stop member 59 is provided for limiting the upward stroke of the arm 45.

In order to adjust the precise position of the anvil head member 23 in its raised position the member is provided with a screw-threaded stem portion 60 having threaded engagement with a recess 61 extending into the end of the anvil member 22 as is clearly shown in Figures 2 and 4 of the drawing. A lock nut 62 is provided for holding the anvil head member in its adjusted position.

In order to release the anvil head member for downward movement whenever desired and independently of the operative movements of the machine as a whole, a manually operable releasing member 63 is provided

which can be forced into engagement with the end of the bolt 30 to press the same from locking engagement with the recess 34. A spring 64 acts to move the releasing member 63 to its inoperative position.

The cushioning device 43' referred to is shown in detail in Figure 11 of the drawing and consists of an outer cylinder 65 which is provided with an eye member 66 for attachment to a lug 67 on the base 10. Within the cylinder 65 a hollow plunger 68 is mounted for sliding engagement therein. The inner end of the cylinder 65 is closed and provided with a relatively small port 69. The outer end of the hollow piston or plunger is provided with ports 70 adapted to be covered or uncovered by longitudinal movement of a cover cap 71 connected to the outer end of the cylinder by means of a pin 72. The cover cap member 71 is attached to the arm 23' through a suitable connecting member 73.

In the operation of the device as a whole a preformed cap or rivet head member 74 is laid in a correspondingly shaped recess formed in the end of the anvil head member 23. The cushion 35 or other work is then placed in position on the anvil head member 23 and the treadle 28 is depressed under the foot of the operator. This action elevates the anvil member 22 and lifts the cushion 35 into engagement with the rivet setting mechanism 14. When the anvil member 22 has reached the desired position of elevation, the spring-pressed bolt 30 snaps into the notch 34 and locks the anvil member in its operative position.

With the parts held in the operative position referred to, the other foot treadle 47 is depressed to bring about the operation of the rivet setting mechanism 14 through the train of connected operating parts already referred to. This brings about the clinching or upsetting of the lower end of the rivet 75 within the hollow side of the cap 74 already referred to. In Figure 10 of the drawing there is shown on an enlarged scale the condition of the parts at the termination of the rivet setting operation.

Following the rivet setting operation referred to, the foot treadle 47 is released whereupon it is lifted under the action of the spring 57 to its elevated position shown in Figure 1 of the drawing. The slide bar 36 is pivoted to the lever 45 at 76 so that in the upward movement of the lever 45 the slide bar 36 is raised to thereby engage the bolt operating member 38 to thereby remove the bolt from its locking position and permit the descent of the anvil member 22 in the slideway 21. It will thus be seen that the release of the treadle 47 at the end of a rivet setting operation automatically brings about the lowering of the anvil member 22 and permits the repositioning of the cushion 35 for

the next succeeding rivet setting operation. Continued operation or repetition of the operative movements is brought about, as will be seen, by the alternate operation of the treadle members 28 and 47. 70

What I claim is:—

1. In a device for tufting cushions, a rivet setting device, an anvil member movable toward and from the rivet setting device, a foot pedal for moving the anvil member 75 toward the rivet setting device to engage a cushion interposed therebetween, mechanical means for locking the anvil member in cushion-engaging position, and a second foot pedal for operating the rivet setting device. 80

2. In a device for tufting cushions, a rivet setting device, an anvil member movable toward and from the rivet setting device, a foot pedal for moving the anvil member toward the rivet setting device to engage a 85 cushion interposed therebetween, mechanical means for locking the anvil member in cushion-engaging position, a second foot pedal for operating the rivet setting device, and means connected to the second foot pedal 90 for releasing the anvil locking means when the rivet setting device has been actuated.

3. In a device for tufting cushions, a rivet setting device, an anvil member movable vertically toward and from the rivet setting 95 device, a foot pedal for raising the anvil member toward the rivet setting device to engage a cushion interposed therebetween, mechanical means for locking the anvil member in cushion-engaging position, a second 100 foot pedal for operating the rivet setting device, and means connected to said second foot pedal for releasing the locking means for the anvil member when the rivet setting device has operated. 105

4. In a device for tufting cushions, a rivet setting device, a frame member having a vertically disposed guideway therein, an anvil member mounted in said guideway for vertical movement toward and from said rivet setting device, means for raising the anvil member toward the rivet setting device to engage a cushion interposed therebetween, a spring-pressed bolt carried by the anvil member for engaging a recess in the 115 frame member and locking the anvil member in its raised position, a bolt retracting member movable longitudinally of said anvil member, means for operating the rivet setting device, and means connected to said operating means for actuating the bolt retracting member to release the anvil member when the rivet setting operation has been accomplished. 120

5. In a device for tufting cushions, a rivet setting device, a frame member having a vertically disposed guideway therein, an anvil member mounted in said guideway for vertical movement toward and from said rivet setting device, means for raising the anvil 125 member

member toward the rivet setting device to engage a cushion interposed therebetween; a spring-pressed bolt carried by the anvil member for engaging a recess in the frame member and locking the anvil member in its raised position, a slideway extending longitudinally of said anvil member, a bolt actuating member extending into said slideway, a bolt retracting member movable along said slideway into and out of engagement with said bolt actuating member, operating means for said rivet setting device, and means connected to said operating means for moving the bolt retracting member to engage the bolt actuating member and retract the bolt to release the anvil member when the rivet setting operation has been accomplished.

6. In a device for tufting cushions, a rivet setting device, a frame member having a vertically disposed guideway therein, an anvil member mounted in said guideway for vertical movement toward and from said rivet setting device, means for raising the anvil member toward the rivet setting device to engage a cushion interposed therebetween, a spring-pressed bolt carried by the anvil member for engaging a recess in the frame member and locking the anvil member in its raised position, a slideway extending longitudinally of said anvil member, a bolt actuating member projecting into the slideway, a cam member movable along said slideway to engage said bolt actuating member, operating means for said rivet setting device, and means connected to said operating means for moving the cam member to release the anvil member when the rivet setting operation has been actuated.

7. In a device for tufting cushions, a rivet setting device, a vertically disposed guide member, an anvil member mounted for vertical movement in said guide member toward and from said rivet setting device, a foot treadle for elevating said anvil member to engage a cushion, a latch for locking the anvil member in elevated position, a foot treadle and connected means for actuating the rivet setting device, and means connected to the last-named treadle for releasing the latch to release the anvil member when the rivet setting device has been operated.

8. In a device for tufting cushions, a rivet setting device, a vertically disposed guide member, an anvil member mounted for vertical movement in said guide member toward and from said rivet setting device, a foot treadle, a link connecting said foot treadle and said anvil member, a latch for holding the anvil member in elevated position, a foot treadle for actuating the rivet setting device,

means connected to said last-named foot treadle for releasing the latch upon the return movement of the foot treadle from rivet setting position, and manually operable means for releasing the latch independently of the foot treadle connection.

9. In a device for tufting cushions, a rivet setting device, a vertically disposed guide member, an anvil member mounted for vertical movement in said guide member toward and from said rivet setting device, a foot treadle, a link connecting said foot treadle and said anvil member, a latch for holding the anvil member in elevated position, a foot treadle for actuating the rivet setting device, means connected to said last-named foot treadle for releasing the latch upon the return movement of the treadle from rivet setting position, spring means for returning the released anvil member to inoperative position, and shock absorbing means for cushioning the return movement of the anvil member.

10. In a device for tufting cushions, a standard, a head member extending horizontally from the upper end of the standard, a rivet feeding device mounted on the head member, a rivet setting device mounted on the head member, a post positioned beneath the rivet setting device, an anvil member movably mounted on the post to reciprocate toward and from the rivet setting device to engage a cushion interposed therebetween, a treadle lever mounted on the post for operating the anvil member, a treadle lever mounted on the standard, a rock arm mounted on the head member, a link connection between the treadle member mounted on the standard and said rock arm, and link connections between the rock arm and the rivet feeding and setting devices for operating the same.

11. In a rivet feeding and setting device, a standard, a head member extending horizontally from the upper end of the standard, a rivet feeding device mounted on the extended end of the head member, a rivet setting device mounted on the extended end of the head member, a work-receiving anvil member mounted beneath said rivet setting device, a treadle lever mounted on the standard and extending to the rear thereof, a rock arm mounted on a rearward portion of the head member, a link connection between the treadle lever and the rock arm, and link connections between the rock arm and the rivet feeding and setting devices for operating the same.

In testimony whereof I affix my signature.

EDWIN B. STIMPSON.
